INVENTOR

UNITED STATES PATENT OFFICE

WILLIAM A. GARDNER, OF NEW YORK, N. Y.

DESIGN FOR A BADGE FOR SPANISH WAR VETERANS

Application filed June 17, 1932. Serial No. 44,119. Term of patent 14 years.

To all whom it may concern:

Be it known that I, WILLIAM A. GARDNER, a citizen of the United States, residing in the borough and county of Bronx and city and State of New York, have invented a new, original, and ornamental Design for Badge for Spanish War Veterans, of which the following is a specification, reference being had to the accompanying drawing, forming part hereof.

The drawing shows a perspective view of a badge for Spanish War veterans, showing my new design, representing the spirit of the War with Spain.

I claim:

The ornamental design for a badge for Spanish War veterans, as shown and described.

Signed at the borough and county of Bronx and city and State of New York this 14th day of June, 1932.

WILLIAM A. GARDNER.
